UNITED STATES PATENT OFFICE

WILHELM AUGUST HOFFMANN, OF BERLIN-KARLSHORST, GERMANY, ASSIGNOR, BY
MESNE ASSIGNMENTS, TO THE TABULATING MACHINE COMPANY, OF NEW
YORK, N. Y.

TYPE HOLDING APPLIANCE

Application filed August 30, 1927, Serial No. 216,400, and in Germany March 26, 1927.

This invention relates to an improvement in typewriting and tabulating machines, especially of that known system, in which an automatic operation of the type bars, assembled in groups side by side and adapted to move independently up and down, is derived from an apparatus controlled by inserted punched cards. The object of the invention is to construct the individual type bars, forming the carriers of a plurality of type bearing members, in such a manner that the whole set of the said members can be replaced or interchanged bodily by another set having diverse denominations, avoiding the necessity of detaching the typeholder bars from the machine. In the constructional form as hitherto designed one of side walls or cheeks holding the type bearing members between them, is made detachable which entails, however, the drawback that the type members lose their guide hold and can fall into disorder, thus rendering the exchange difficult and wearisome. This drawback and others are obviated in the present constructional form which permits an easy exchange of complete sets of type members without altering the position of the type holder bars in the machine.

The main feature of the invention is, that a separate holder frame is used which comprises the type members together with their springs, and constitutes a self contained exchange body enclosed between the cheeks of the upper end of the bar forming a forked holder. A suitable closing cap or locking member is put over the said forked end.

The invention is illustrated diagrammatically and by way of example on the accompanying drawings on which Figure 1 is a side view of a type carrier bar, the forked upper end of which contains an exchangeable holder comprising nine type members; Fig. 2 is a separate view of the holder, Figure 3 a section through the holder frame taken on the line X—X of Figure 2, Figure 4 a front view of the assembled members, partly in section, and Figures 5, 6 and 7 are perspective representations, Fig. 5 showing a closing cap, Fig. 6 showing a cap piece which can be put

upon the forked upper end of the bar and Fig. 7 showing this upper end.

The shank *s* of the type carrier bar is forked at its upper end, forming two parallel cheeks *p* and *q*, (Fig. 7), the uppermost portions or rims of which are so bent and curved as to form two lips *p*¹ and *q*¹. There is a gap between the cheeks *p* and *q*, adapted to receive the type holder frame *a* (Figs. 2 and 3) which is shaped somewhat like a comb and provided with holes *i* extending in the direction of the gaps between the teeth of the comb. The type pins *b* are formed with reduced shanks guided in these holes and the pin shanks which extend into the gaps between the teeth of the comb are surrounded with helical compression springs *f* bearing at one end against prismatic abutments *v* forming the rear ends of said shanks, and at the other end against an annular shoulder surrounding the hole *i*. The abutment *v* is that part of the individual type member upon which is exerted from the rear the blow by which the type is pushed forward into its printing position. The individual type members comprising each a portion *b* and *v* and a connecting shank *p* may be permanently assembled on the frame *a* since the exchange of type is ordinarily made by an interchange of frames *a* with the attached type. Obviously the shank connecting the portions *b* and *v* of the type may be separable as by having the said shank detachably connected within the portion *b* by means of screw threads or otherwise. Below the abutment heads *v* an immovable supplementary lug *r* is provided at the holder frame *a*. The type members are guided within the laterally open gaps of the frame or comb *a*.

The completely filled holder frame *a* constitutes the self contained exchange body which can easily be inserted into and removed from the forked upper end of the bar *s*, i. e. between the cheeks *p* and *q*. Means, such as elastic or spring supported projections and cavities for their reception, are provided at the holder frame *a* on the one hand and the cheeks *p* and *q* on the other hand in order to retain the holder frame *a* in proper position between the members *p* and *q*. This fastening may be completed or supplemented by

means of a detachable locking member, or members, for instance such as shown in Figs. 4-6, which comprise a clamping U-shaped member *g* having curved lips *g*¹ *g*² adapted to engage with the curved portions of the lips *p*¹ *q*¹, that is to say, to be slid over them from either side so that the cheeks *p* and *q* cannot spread apart but remain in intimate contact with the holder frame *a* inserted between them. Finally, the cap *k* is slid onto the combined parts *g* *g*¹ *g*² and *p a q*, whereby the closure or locking is completed.

I wish it to be understood that other locking means than those just described may be employed in connection with the assembled parts of the type holding device. In view of the necessity that the type carrier bars in forming a group are arranged closely side by side and contact with each other at their lateral surfaces, care must be taken, that the upper closure means do not protrude over these surfaces.

The inner faces of the cheeks *p* and *q* act as positive guides for the abutment shanks *v* which slide in the recesses *u*. Owing to the type members *b* being retained together in the frame *a* the exchange can be effected very easily without the necessity of removing the type carrier bar from its proper position. It is thereby rendered possible to substitute quickly and easily for instance a set of numeral types for alphabetical types or types of diverse denomination for a set of types of other character, or vice versa. For the purpose of effecting such interchanging operation at any time, a plurality of holders comprising type members of different character may be provided for.

Claims:

1. An exchangeable appliance for type holders appertaining to typewriting tabulating machines, comprising, in combination with type carriers bars arranged side by side and forming groups, of a pair of parallel upwardly extending cheeks forming the upper end of the respective bar, a frame like piece, inserted exchangeably between said cheeks and adapted to receive the type members as located in and guided by recesses of the said piece also comprising individual springs pertaining to the individual type members and adapted to shift the types back into their normal position after every actuation.

2. An exchangeable appliance for type holders appertaining to type writing tabulating machines, comprising, in combination with type carrier bars arranged side by side and forming groups, of a pair of parallel upwardly extending cheeks forming the upper end of the respective bar, a recessed comb like member inserted exchangeably between said cheeks and adapted to receive the type members as located in and guided by recesses of the said piece also comprising individual springs pertaining to the individual type

members and adapted to shift the types back into their normal position after every actuation.

3. An exchangeable appliance for type holders appertaining to type writing tabulating machines, comprising in combination with type carrier bars arranged side by side and forming groups, of a pair of parallel upwardly extending cheeks forming the upper end of the respective bar, a frame like piece, inserted exchangeably between said cheeks and adapted to receive the type members as located in and guided by recesses of the said piece also comprising individual springs pertaining to the individual type members and adapted to shift the types back into their normal position after every actuation, and means adapted to be attached detachably upon the said cheeks and to retain the inserted type carrying member between them.

4. A type carrier comprising a shank, a clamping element integral with said shank and a holder containing a plurality of type elements movable with respect to said holder for printing operations adapted to be releasably attached to said shank by said clamping element.

5. A type carrier comprising a shank having a forked portion, a type container adapted to be releasably secured to the shank by said forked portion and means for causing said portion to grip said container.

6. In a type carrier, a holder containing a plurality of type elements movable with respect to said holder for printing operations, and a shank having a clamping element adapted to releasably receive said holder.

7. A type carrier comprising a shank, a clamping element on said shank, a holder containing a plurality of type elements adapted to be received by said clamping element and removable means for causing said clamping element to grip said holder.

8. In a type carrier, a holder, a plurality of type elements mounted therein and adapted for individual character printing, a shank having a clamping element adapted to receive said holder and releasable locking means for holding said clamping element in clamped position.

9. A type carrier, a holder carrying a plurality of type elements, a clamping element for receiving said holder, a shank integral with one end of said clamping element and means cooperating with the other end of said clamping element to effect clamping action on said holder.

10. A type carrier comprising a holder containing a plurality of type, a shank having a forked portion for securing said holder and removable means for drawing said forked portion together to grip said holder whereby said holder may be freely removable.

In testimony whereof I affix my signature.
WILHELM AUGUST HOFFMANN.
